UNITED STATES PATENT OFFICE.

JOHN EVANS TAYLOR, OF CAMDEN, OHIO, ASSIGNOR OF ONE-THIRD TO J. F. KNEPPER,
OF WHITE WATER, INDIANA, AND ONE-THIRD TO F. E. TAYLOR, OF CAMDEN, OHIO.

WINDOW-SCREEN.

1,161,084

Specification of Letters Patent. Patented Nov. 23, 1915.

Application filed February 19, 1915. Serial No. 9,220.

To all whom it may concern:

Be it known that I, JOHN EVANS TAYLOR, a citizen of the United States, residing at Camden, in the county of Preble and State 5 of Ohio, have invented certain new and useful Improvements in Window-Screens, of which the following is a specification.

My invention relates to window screens which are so constructed that they are 10 removable from their operative position in a window frame.

In this connection the main object of my invention resides in providing a structure whereby the screen itself may be adjusted 15 two ways, that is, as regards its width dimension and its height dimension. This result I accomplish by a peculiar construction of slide strip forming two sides of each of the various sections, these slide 20 strips being so formed that the complementary strips will interlock in such manner to prevent all relative movements except longitudinally.

My invention also resides in providing a 25 structure whereby this screen may be readily attached to practically any type of window frame.

The preferred embodiment of my invention 30 is shown in the accompanying sheet of drawings, in which similar characters of reference designate corresponding parts, and in which:

Figure 1 is a face view of my screen shown assembled, the broken lines representing the same in extended position, Fig. 35 2 represents an application of my invention, Fig. 3 is a view in perspective showing a portion of the guide strips used by me, Fig. 4 is a view in cross section of my screen showing the same held in elevated position, and, Fig. 5 is a view in perspective of a 40 spring clip used by me.

In these drawings, the screen proper is 45 shown as being formed of four rectangular sections designated 1, these sections being of the usual screen material and being provided with edgings or edge strips 2 along two edges of each section. The remaining two edges designated 3 are provided with 50 slide strips, these strips being practically U-shape in section, as is shown in Fig. 4, although one leg of one of these sections is preferably bent inwardly to present an angle as is shown at 4 to lie in a substantially 55 central plane with respect to the slide

strips as a whole. It is to this inwardly bent portion that the screen itself is attached. The similar leg of the other slide strip which telescopes or slides within the one just previously described is bent to assume 60 the shape designated at 5 to form a means of attachment of its screen section. By referring particularly to Fig. 4, it will be noted that these slide strips are so formed that the complementary strips interlock with each other 65 to permit relative movement only in a longitudinal direction and it is by means of this structure of slide strip that my screen is permitted a width adjustment as well as a height adjustment. In order that the various 70 screen sections may be held in close relation with each other, I find it desirable to insert small clip fasteners after the manner shown at 6 in Figs. 1 and 2, this being done, however, after the screen sections 75 have been properly adjusted to the window.

In order that my screen may be so mounted as to be capable of vertical movement in a window framework, I have provided 80 U-shaped guide strips designated 7 and 8, the guide strips for the side of the window frame being preferably made of the two sections in order that the same length of 85 guide strips may be adapted to window frames of various heights. These guide strips are designed to be attached to the window framework through apertures such as shown at 9 or the brads or screws may be driven directly through the metal itself. The section 8 is preferably provided with 90 overlapping ears bent down to the form shown at 10 in order that the adjoining ends of the two sections forming each guide strip may always be maintained in 95 alinement.

I have provided a resilient clip of the nature shown in detail in Fig. 5 in the event that it is desired to maintain the screen in an elevated position. This clip is provided 100 with a pair of bent ends 12 adapted to be driven into the window at any desired position, but so arranged that the inwardly bent portion 13 thereof will lie in the path of travel of the screen itself. When the screen is pushed up to assume the position shown in Fig. 4, the inwardly bent portions 105 4 of the slide strips will rest upon the shelf portions 14 of this clip and thus it will be apparent that the screen as a whole may 110 be held in this elevated position. When it

is desired to lower the same, the clip is manually forced out of engagement with the screen and the same then slides down into lowered position, it being understood that it is always held confined within the guide strips 7 and 8.

From the foregoing, it will be apparent that I have provided a screen capable of adjustment in two directions. This enables 10 me to fit practically any size of window now in use and also permits me to adjust the amount of screened opening desired.

What I claim, is:

15 A collapsible screen comprising four rectangular sections, edgings on two sides of each section, slide strips on the remaining

two edges of each section so formed that the complementary strips all interlock to permit longitudinal movement only, U-shaped guide strips adapted to be attached to the window frame and extending its entire height, and a spring clip located adjacent the upper end of the window frame arranged to hold the screen in elevated position.

In testimony whereof I affix my signature in presence of two witnesses.

JOHN EVANS TAYLOR.
